REED MUSICAL INSTRUMENT

Hugh W. Loney, Elkhart, Ind., assignor to C. G. Conn, Ltd., Elkhart, Ind., a corporation of Indiana

Application March 8, 1935, Serial No. 9,971

8 Claims. (Cl. 84—385)

My invention relates to reed musical instruments, and particularly to the octave sockets therefor.

In reed musical instruments, more especially the saxophone, in which the conventional type of octave key socket is incorporated, the air pulsations issuing from the open octave hole impinge directly upon the soft pad of the octave key associated therewith and cause a buzzing sound, this sound being particularly conspicuous on high A of saxophones and to some degree when the adjacent note (B—flat) is played, thereby materially impairing the tone quality.

The principal objects of my invention are, to reduce the velocity of the air pulsations issuing from the octave socket to a negligible degree prior to impingement thereof on the soft pad of the octave key, and to cause the air to eddy at an appreciable distance below the top of the octave socket, or keypad seat, thereby causing the flow of air pulsations to lose their violence before reaching the top of the octave socket.

Other and more specific objects of my invention are mentioned and described herein.

3 The invention is illustrated in the accompanying drawing, wherein

Figure 1 illustrates a side view of a saxophone mouthpipe to which my invention is applied;

Figure 2 illustrates a section taken on line 2—2 of Figure 1; and

Figure 3 illustrates an enlarged sectional view of the octave socket alone.

Similar numerals of reference indicate like parts throughout the several views on the drawing.

Referring now to the details of the drawing the numeral 1 indicates a type of saxophone mouthpipe now in general use which is provided with the curved octave key bar 2 which is pivotally mounted on the mouthpipe at 3, the lower end of said key bar being provided with the usual ring 4 for tilting said key bar, as is well known in the art. The upper end of the bar 2 is provided with the usual soft key pad 5 which is normally held in contact with the upper octave socket 6 by a spring 7, also well known in the art.

The present common type of octave socket consists of a tubular member having a cylindrical bore drilled axially thereof, and it is this octave socket construction which causes the air pulsations to impinge directly and violently upon the soft pad 5, producing a buzzing sound which is especially conspicuous on high A of saxophones.

It is this disagreeable and tone impairing buzz

that my invention is intended to, and does, obviate.

My improved octave socket is indicated generally by the numeral 6, the shank portion of which is indicated by the numeral 14, said shank section being adapted to be rigidly secured in a suitable opening formed in the wall of the mouthpipe and which may project to the interior of said pipe, as illustrated in Fig. 2 of the drawing. The upper end of the socket shank section 10 may terminate in a shoulder 8 which may engage the exterior adjacent surface of the mouthpipe. As illustrated, that portion of the socket 6 which is exteriorly of the mouthpipe is somewhat flared, but such a flared condition thereof 15 is not essential to the merits of my improved socket.

The bore of my octave socket may comprise the outwardly flaring conical bore section 10 at the top end thereof, the inner or lower end of said bore being connected with the relatively short conical bore section 11 by an annular beveled shoulder 12, said conical section 11 terminating at the upper end of the cylindrical bore section which is in direct communication with the interior of the pipe 1. In this socket bore construction the top section 10 effects a wide angle of flare, whereby a smooth flow of the air pulsations is effectually prevented, the best pulsation deterrent results being obtained by a 29 degree flare, 30 as illustrated. And to induce the necessary air eddies the lower section 11 of the conical bore is formed at a slightly different angle (27 degrees) and of reduced diameter, said bores 10 and 11 being connected by the beveled annular shoulder 12.

As illustrated, the annular shoulder 12 is beveled relatively to the socket axis at 150 degrees which proportions have been found by extensive experimenting to be the most effective in inducing the necessary air eddies prior to the entrance of the air pulsations to the top socket section 10.

It will thus be apparent that the combination of the conical bores 10 and 11 connected by the beveled shoulder 12 provide, generally, a stepped, 45 or interrupted, conical bore for the socket element 6; or, in different language, a pair of spaced conical bores of different sizes which are connected by an annular shoulder extending circumferentially of the socket interior. It will be noted that the conical bore section 10 extends downward substantially into the shank section 14 of the socket body, and that the bores 11 and 13, as well as beveled shoulder 12, lie wholly within the socket shank section. 55

While I have shown my improved octave socket applied to the mouthpipe of a saxophone it will be apparent, to those skilled in the art, that it may be applied also to any part of a reed musical instrument body where such a socket could be operatively applied.

I claim:

- 5 1. A reed musical instrument provided with a padded key and a socket therefor, said socket being provided with a pair of spaced conical bores.
- 10 2. A reed musical instrument provided with a padded key and a socket therefor, said socket being provided with a pair of spaced conical bores connected by an annular shoulder.
- 15 3. A reed musical instrument provided with a padded key and a socket therefor, said socket being formed with a pair of spaced conical bores, one of said bores being connected with a cylindrical bore.

4. A reed musical instrument provided with a padded key and a socket therefor, said socket being provided with a pair of spaced conical bores connected by an annular beveled shoulder.

5. In a reed musical instrument, an octave key socket having a shank section, said socket being provided with a conical stepped bore which extends into said shank section.

6. In a reed musical instrument, an octave key socket having a shank section, said socket being provided with a conical stepped bore which extends into said shank section, one of said conical bores joining a cylindrical bore in said socket.

7. In a reed musical instrument, an octave key socket provided with a conical stepped bore.

8. In a reed musical instrument, an octave key socket provided with a pair of spaced conical bores connected by an annular shoulder.

HUGH W. LONEY. 20
